(57) **CLAIM**

The ornamental design for a magnetic weapon mount, as shown and described.

DESCRIPTION

FIG. 1 is a top perspective view of a magnetic weapon mount according to one embodiment of the claimed design; FIG. 2 is a bottom perspective view thereof;

FIG. 3 is a top plan view thereof;

FIG. 4 is a bottom plan view thereof;

FIG. 5 is a first-side elevational view thereof;

FIG. 6 is a second-side elevational view thereof;

FIG. 7 is an exploded top perspective view thereof illustrating the top and bottom parts separated;

FIG. 8 is a bottom perspective view thereof;

FIG. 9 is a top perspective view of a magnetic weapon mount according to a second embodiment of the claimed design;

FIG. 10 is a bottom perspective view thereof;

FIG. 11 is a top plan view thereof;

FIG. 12 is a bottom plan view thereof;

FIG. 13 is a first-side elevational view thereof;

FIG. 14 is a second-side elevational view thereof;

FIG. 15 an exploded top perspective view thereof illustrating the top and bottom parts separated;

FIG. 16 is a bottom perspective view thereof;

FIG. 17 is a top perspective view of a magnetic weapon mount according to a third embodiment of the claimed design;

FIG. 18 is a bottom perspective view thereof;

FIG. 19 is a top plan view thereof;

FIG. 20 is a bottom plan view thereof;

FIG. 21 is a first-side elevational view thereof;

FIG. 22 is a second-side elevational view thereof;

FIG. 23 is an exploded top perspective view thereof illustrating the top and bottom parts separated; and,

FIG. 24 is a bottom perspective view thereof.

The broken lines in the drawings depict environmental objects that form no part of the claimed design.
